FOREIGN PATENT DOCUMENTS

GB 2011070 * 3/1991

Primary Examiner — T Chase Nelson*Assistant Examiner* — Kelly L Gross(74) *Attorney, Agent, or Firm* — FisherBroyles, LLP(57) **CLAIM**

The ornamental design for a contact lens disposal container as shown and described.

DESCRIPTION

FIG. 1 is a top perspective view of a contact lens disposal container embodying the design;

FIG. 2 is a front view therein;

FIG. 3 is a right side view thereof, the left side view being a mirror image;

FIG. 4 is a top view thereof with a lid in the closed position;

FIG. 5 is a top view thereof with a lid in the open position; and,

FIG. 6 is a bottom view thereof.

The broken lines in FIG. 5 depict portions of the contact lens disposal container that form no part of the claimed design.
